WATER HEATER THERMOSTAT

Henry C. Keck, Pasadena, Calif., assignor to Robertshaw-Fulton Controls Company, Greensburg, Pa., a corporation of Delaware

Application January 14, 1955, Serial No. 33,986

Term of patent 14 years

(Cl. D52—1)

The figure is a perspective view of a water heater thermostat, showing my new design.

The opposite side of the water heater thermostat is the same in appearance as the side shown, and the rear is substantially plain.

I claim:

The ornamental design for a water heater thermostat, as shown and described.
